UNITED STATES PATENT OFFICE.

EZRA C. FITCH, OF MANCHESTER, MASSACHUSETTS.

DESIGN FOR A WATCH-DIAL.

SPECIFICATION forming part of Design No. 34,261, dated March 26, 1901.

Application filed February 26, 1901. Serial No. 49,011. Term of patent 14 years.

To all whom it may concern:

Be it known that I, EZRA C. FITCH, a citizen of the United States, residing at Manchester, in the county of Essex and State of Massachusetts, have invented and produced a new and original Design for a Watch-Dial, of which the following is a specification, reference being had to the accompanying drawing, forming part thereof.

My invention consists in a design for a dial of a watch or similar article.

I have illustrated my design in the accompanying drawing, in which is shown a plan view of a dial, exhibiting my new design.

As shown in the drawing, the leading and essential feature of this design is an outer portion C, arranged in a generally annular form, included between the periphery A of the dial and the inner circular line B, concentric with said periphery and at a suitable distance therefrom. The portion C of the design is formed of a number of small ornamental forms or figures d d, contiguous to each other, each of which resembles in outline the form of a somewhat-truncated acorn or a shield. From each point of junction between the acorn-shaped or shield-shaped figures d d a small pyramidal point e projects inward toward the circular line B. The acorn-

shaped or shield-shaped figures d d are arranged with their broad portions nearest to the circular line B and with their apexes pointed toward and substantially touching the periphery A of the dial. In the inner side of the acorn-shaped or shield-shaped figures d d, the same being the side thereof which is nearest to the inner circular line B, is a recess ff, the said recesses being usually placed symmetrically in the middle of the said inner side or boundary-line of the said acorn-shaped or shield-shaped figures, which are usually thirty in number.

Having described my invention, what I claim as new, and desire to secure by Letters Patent of the United States, is—

The design for a watch-dial herein shown and described.

In testimony whereof I, EZRA C. FITCH, have affixed my signature hereto, in the presence of witnesses, at the borough of Manhattan, in the city of New York, State of New York, this 15th day of February, 1901.

EZRA C. FITCH.
